UNITED STATES PATENT OFFICE.

RUDOLF KÜHN, OF RORSCHACH, SWITZERLAND.

GENERATOR FOR ACETYLENE GAS.

SPECIFICATION forming part of Letters Patent No. 600,727, dated March 15, 1898.

Application filed July 10, 1896. Serial No. 598,632. (No model.) Patented in Austria March 30, 1896, No. 47/1,119; in Switzerland April 27, 1896, No. 12,163; in France May 2, 1896, No. 256,059; in Germany May 2, 1896, No. 94,738; in Belgium October 26, 1896, No. 124,191, and in Italy November 26, 1896, No. 42,912.

To all whom it may concern:

Be it known that I, RUDOLF KÜHN, a citizen of the Republic of Switzerland, and a resident of Rorschach, Switzerland, have invented 5 a certain new and useful Generator for Acetylene Gas, (which has been patented in the following countries, viz: Switzerland, No. 12,163, dated April 27, 1896; Austria, Act. No. 47/1,119, dated March 30, 1896; France, No. 256,059, dated May 2, 1896; Belgium, No. 124,191, dated October 26, 1896; Italy, R. G. 42,912, dated November 26, 1896, and Germany, No. 94,738, dated May 2, 1896,) of which the following is a specification.

15 In the acetylene-gas apparatus heretofore in use, as well as in the apparatus for generating the ordinary illuminating-gas, gas-holders of variable volume were used, such as the gasometer-drums and the like, in which the 20 pressure of the gas being generated is held constant by the gradual displacement of the water in the storage-cylinder, caused by the gradually-inflowing quantities of gas, so that the size of the drum is increased. This arrangement is too cumbersome to be employed 25 for the storage of acetylene gas, and my improved apparatus contains, therefore, a storage cylinder or receiver of constant volume, which is connected with a generator in such 30 a manner that the charging of the receiver with acetylene gas is effected by the gradually-increasing pressure of the generated gas. The gas can therefore be stored up in the receiver at any desired pressure, so that in any 35 comparatively small receiver large quantities of gas can be stored, and as the large and cumbersome storage apparatus are dispensed with a much smaller and simpler receiver for acetylene gas is obtained. For this reason 40 my improved acetylene-gas generating and storing apparatus is especially adapted for stationary illuminating plants, especially when it is considered that the illuminating power of acetylene gas is five times that of 45 the compressed oil-gas. My apparatus is therefore designed to be used in place of the oil-gas plants for supplying railway-cars with compressed gas as well as for supplying gas for lighthouses, light-ships, buoys, &c. Be- 50 sides, the greater illuminating power of acety-

lene gas as compared to oil-gas the oil-gas plants required complicated apparatus for generating the gas, which has then to be compressed by means of pumps into the receivers up to a pressure of six atmospheres. 55 The erecting and working of these oil-gas plants were always connected with a number of complications and objections, while in my improved apparatus the acetylene gas generated from the mixture of calcium carbide and water is discharged under its own pressure of several atmospheres into the receiver and is gradually compressed by the continuous generation and supply of gas, so that by the simple construction and functioning of the apparatus hardly any supervision and attention, 60 excepting the charging of the materials, are required.

In the accompanying drawings, Figure 1 is 70 a vertical central section of my improved generator. Fig. 2 is a similar view taken at right angles to Fig. 1. Fig. 3 is a top view of the generator. Fig. 4 is a top view similar to Fig. 3, some of the parts mounted on the head being removed. Fig. 5 is a central vertical section of a modified form of generator. Fig. 6 is a top view thereof. Figs. 7 and 8 are vertical sections through the head of the generator respectively at right angles to each other. 75

80 Similar letters of reference indicate corresponding parts.

Referring to the drawings, A represents the generator constructed in accordance with my invention. The generator A is formed of a 85 hollow seamless cylinder J, which is closed at the lower end and which is provided with a head K, provided with a stop-cock, as well as other accessories, such as a pressure-gage, &c. At the interior of the cylinder J is arranged a cylindrical basket D, formed of wire-gauze, which is charged with calcium carbide and which is provided at its bottom with a pin E, so that the basket D can be supported at some distance from the bottom of the cylinder J, so that the lime cement, which is formed by the decomposition of the calcium carbide, cannot settle on the latter and retard thereby the gas-generating process. In the head K, which is hermetically connected by 90 95 100

its frusto-conical neck with the corresponding neck of the cylinder J, are arranged the stop-cock L, an outlet-tube F, to which the pipe which leads to a receiver is attached, a pressure-gage G, and a relief-valve H for the surplus pressure.

In the construction shown in Figs. 1 to 4 the head K is attached to the cylinder J by means of a pivoted yoke O and a screw P, passing through the yoke and operated by a hand-crank at its upper end. The body L⁰ of the vertically-arranged stop-cock L' is provided at its lower end with a hook-shaped latch or lug M, which when the stop-cock L' is closed, as in Fig. 3, engages the bail m of the basket D, containing the calcium carbide, so as to support the basket. When the stop-cock L' is placed in open position, as shown in Fig. 4, the basket is dropped into the water in the cylinder J by the disengagement of the latch M from the bail. It is therefore necessary that the cylinder J be partly filled with water up to the bottom of the basket containing the calcium carbide, after which the bail m is placed on the latch M and the head K placed on the upper end of the cylinder J and then firmly secured by the screw P. When the tight connection of the head with the cylinder is obtained, the stop-cock L' is turned and opened, by which motion the basket is automatically detached from the latch M and dropped into the water in the generator.

In the construction shown in Figs. 5 to 8 the stop-cock is arranged in a horizontal position and the body L² of the same provided at its inner end with an eccentric-pin z, which is connected by a rod S with a fulcrumed latch M' in such a manner that when the stop-cock is closed, as shown in Fig. 5, the latch M' engages the bail m of the basket D, while when the stop-cock is opened, as

shown in Fig. 7, the basket is dropped into the water at the lower part of the generator, so that the generation of the acetylene gas 45 takes place.

Having thus described my invention, I claim as new and wish to secure by Letters Patent—

1. In a generator for acetylene gas, the combination of a cylinder, a tightly-fitting head on the same, provided with a stop-cock, a basket for the calcium carbide, in said cylinder, and means for suspending said basket from the head and dropping the same into the 55 water in the cylinder when the stop-cock is opened, substantially as set forth.

2. In a generator for acetylene gas, the combination of a cylinder, a tightly-closing head on the same, a basket for the calcium carbide, 60 provided with a bail at its upper end, means for suspending said basket above the water in the cylinder, while the stop-cock is closed, and means for releasing said basket when the stop-cock is opened so that the basket is lowered into the water, substantially as set forth.

3. In a generator for acetylene gas, the combination with a cylinder, a tightly-fitting head on the same, means for attaching said head to the neck of the cylinder, a stop-cock in said 70 head, a screen-basket in said cylinder provided with a pivoted bail at its upper end, means connected with the stop-cock for suspending the basket when the stop-cock is in closed position and for dropping the basket 75 in the water in the cylinder when the stop-cock is open, substantially as set forth.

In testimony whereof I hereunto sign my name, in the presence of two subscribing witnesses, this 13th day of May, 1896.

RUDOLF KÜHN.
